UNITED STATES PATENT OFFICE.

GEORGE L. SCHEEL, OF CHICAGO, ILLINOIS.

HAIR-WAVING DEVICE.

1,195,929.

Specification of Letters Patent. Patented Aug. 22, 1916.

Application filed September 25, 1915. Serial No. 52,677.

To all whom it may concern:

Be it known that I, GEORGE L. SCHEEL, a citizen of the United States, and a resident of the city of Chicago, county of Cook, and State of Illinois, have invented certain new and useful Improvements in Hair-Waving Devices, of which the following is a specification.

My invention relates to improvements in hair-waving devices and has for its object the production of a device of this character which will be of simple construction, one which may be readily and easily manipulated, and one which will be highly efficient in use.

Other objects will appear hereinafter.

The invention consists in the combinations and arrangements of parts hereinafter described and claimed.

The invention will be best understood by reference to the accompanying drawing, forming a part of this specification, and in which—

Figure 1 is a side elevation of a hair waving device embodying my invention, and Fig. 2 is an end elevation thereof.

The preferred form of construction as illustrated in the drawing comprises a hair engaging element consisting of co-operating jaws 1 and 2. Said jaws are of elongated channel form, the jaw 2 being adapted to snugly embrace the jaw 1 as clearly shown in Fig. 2. Said jaws are pivotally connected together at corresponding ends as at 3 so as to permit of the opposite ends of said jaws being moved toward and from each other as will be readily understood. The longitudinal edges of the jaw 1 are turned back as at 4 in order to constitute channels for the reception of the corresponding edges of the jaw 2 as clearly shown in Fig. 2 and for a purpose which will be hereinafter set forth.

The jaw 1 is adapted to snugly engage with the cylindrical heating portion 6 of a hair drier 7 the details of which form the subject matter of a co-pending application. The jaw 1 is formed at its respective ends with inwardly extending ears 5 adapted to embrace the portion 6 of the device 7 in order to securely lock the hair engaging device thereto. With this arrangement it will be seen that the hair engaging device or hair waving device proper may be readily and easily engaged with or disengaged from the portion 6 by sliding the former longitudi-

nally of said portion to effect engagement or disengagement of the ears 5 therewith.

The device 7 is provided with a handle 8 at the under side of which is provided an air bulb 9. Secured to the rearward end of jaw 2 is a handle 10 provided at its rearward end with a grip 11. The arrangement is such, as will be seen, that rocking of jaw 2 may be effected through engagement with the grip 11. The bulb 9 serves to normally hold said handle grip in such a position that the jaw 2 is in elevated or inoperative position. Upon upward tilting of the handle 10, in order to effect downward swinging of jaw 2 to operative position, the bulb 9 will be depressed as shown in Fig. 2 so that upon release of said handle the same will be automatically locked downwardly and hence jaw 2 locked upwardly to inoperative position through the resiliency of said bulb. Thus with this arrangement it will be seen that the heating element of the hair drying device 7 is utilized to hold and heat the jaws 1 and 2 and the bulb 9 of the device 7 is utilized to effect automatic rocking of the jaw 2 to inoperative position.

In using the device for hair waving, the hair is interposed between the jaws 1 and 2 whereupon the jaw 2, through engagement of the grip 11, is rocked downwardly to securely clamp the hair between said jaw and the jaw 1. The hair will of course be provided with a wave corresponding with the transverse formation of the jaws 1 and 2. Through the turned back formation of the longitudinal edges 4 of jaw 1 the hair will be bent upwardly at the edges of jaw 2 and thus result in the formation of comparatively sharp turns at the ends of the large wave which is formed between the jaws 1 and 2. This is of particular advantage in forming successive waves in the hair since it serves to designate the terminals of the preceding wave and thus facilitate proper positioning of the device in the formation of the succeeding wave.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Letters Patent is:

1. In a device of the class described, the combination of a heating element; a handle on said heating element; a hair engaging element in proximity with said heating element, said engaging element comprising two pivotally connected jaws; a handle for 10 pressing one of said jaws toward the other; and a depressible air bulb on said heating element and positioned under the handle thereof adapted for engagement with said jaw handle for normally holding said jaws 15 separated, substantially as described.
2. In a device of the class described, the combination of a heating element having a substantially cylindrical portion; a hair engaging element comprising two elongated

channel formed pivotally connected members, one of said members embracing said cylindrical portion of said heating element, the other of said members being adapted to embrace said first mentioned member; a handle on said last mentioned member for 25 rocking the same; and an air bulb on said heating element adapted for engagement with said handle to normally hold said engaging members separated, substantially as described.

In testimony whereof I have signed my name to this specification in the presence of two subscribing witnesses.

GEORGE L. SCHEEL.
